E. LAROCHE,
FOUNTAIN BRUSH,
APPLICATION FILED OCT. 3, 1919.

1,350,415.

Patented Aug. 24, 1920.

Inventor
Emile Laroche
By William Clinton
Attorney

UNITED STATES PATENT OFFICE.

EMILE LAROCHE, OF MONTREAL, QUEBEC, CANADA.

FOUNTAIN-BRUSH.

1,350,415.

Specification of Letters Patent. Patented Aug. 24, 1920.

Application filed October 3, 1919. Serial No. 328,178.

To all whom it may concern:

Be it known that I, EMILE LAROCHE, a subject of the King of Great Britain, residing at Montreal, Province of Quebec, 5 Canada, have invented certain new and useful Improvements in Fountain-Brushes; and I do hereby declare that the following is a full, clear, and exact description of the invention, such as will enable others skilled 10 in the art to which it appertains to make and use the same.

The present invention relates to fountain brushes and more particularly to that class which is used for scrubbing, cleaning or polishing floors or walls, and the principal object of the invention is to provide an improved device of this character, so constructed as to provide for convenient and ready control of the delivery of the water or polishing fluid, while the user is manipulating 20 the brush.

Another object of the invention is to devise a brush of the character specified which can be manufactured on a commercial scale 25 or one which is not difficult to produce as to be beyond the reasonable cost of such contrivance.

With the above and other objects in view which will hereinafter appear as the description continues, the invention consists of the novel features of construction, combination and formation of parts as will be hereinafter more fully described and particularly pointed out in the appended claims.

In the accompanying drawings has been shown a simple and preferred form of the invention, it being, however, understood that no limitation is necessarily made to the precise structural details herein exhibited, but 40 the right is hereby reserved to any changes, alterations or modifications to which recourse may be had that come within the scope of the claims without departing from the spirit of the invention or sacrificing the 45 efficiency of the same.

In the accompanying drawings:

Figure 1 is a perspective view of the improved brush;

Fig. 2 is a longitudinal central section 50 taken through the brush, partly in elevation, constructed in accordance with the present invention;

Fig. 3 is an enlarged fragmental longitudinal section illustrating the operation of 55 one of the valves; and,

Fig. 4 is a vertical section taken through one of the valves, with the valve stem in elevation.

Referring to the drawings, 1 designates the body or casing of my improved fountain brush, preferably constructed of sheet metal and which serves as a reservoir for a supply of water or polishing fluid. A bottom piece 2, preferably constructed of wood, is secured to the base 3 of the casing 1 and 60 is recessed to receive the butt ends of the bristles 4 which may be secured therein in any manner.

The base 3 of casing 1 is formed with the enlargements 5 in which ports 6 are provided. These ports 6 at their upper ends 70 register with the inverted conical openings 7 which communicate with the interior of casing 1, while the lower part of the enlargements 5 form annular flanges 8 which are 75 provided with openings registering with the ports 6.

A fluid distributing pipe 9 has its opposite ends 10 bent at right angles and the said ends are adapted for insertion within the 80 openings in the annular flanges 8 of the base enlargements 5.

The pipe 9 extends flush with the bottom piece 2 and is provided with perforations 11 through which passes the liquid contained in 85 the reservoir or casing 1, to discharge the same upon the underside of the bottom piece and bristles 4.

The fluid outlets are controlled by two needle valves 12, each comprising a stem 13 90 having pointed ends 14 adapted to seat in the conical openings 7 in the base of casing 1, to control the passage of the liquid from the casing 1 to the pipe 9.

These needle valve stems 13 are adjustably secured in the enlarged ends 15 of a support 16, mounted within the hollow interior of casing 1, and at its medial part, said support 16 has connected thereto a rod 17, which is slidably mounted in an enlargement 18 100 formed on the upper wall of said casing 1. Rod 17 extends upwardly from the top of casing 1 and has an elongated presser bar 19 secured thereto.

The valve stems 13 are normally tensioned 105 toward the outlet openings 6, by means of a spring 20, which is coiled around the rod 17. A disk 21 is mounted on said rod 17 and at the opposite ends the spring 20 engages the disk 21 and the lower surface of 110

the enlargement 18 serving to tension the rod 17 inwardly, thus holding the valve ends 14 in the seats 7.

Washers 22 are mounted adjacent the 5 valve outlet openings and provide a tight union of the valves at their seating point.

A handle 23 is secured to the top of casing 1 and the presser bar 19 extends in alinement with said handle.

10 The valve stems 13 may be adjusted with respect to the seats 7, by means of their bolt portions 24, which extend through the top of casing 1 and when the said bolt portions are adjusted the valve stems may be regulated up or down in the support enlargements 15. These valve stems 13, have their pointed ends 14 normally spaced from the seats 7 and when adjusted to or from the seats may close or open the passages from 20 the reservoir.

A tap plug 25 is mounted in an opening in the top of the casing 1, and the liquid may be introduced into the reservoir casing 1, through the said opening.

25 In use, the brush handle 23 is grasped by the hand of the operator and the fingers are placed under the presser bar 19, which action elevates the presser bar 19 against the tension of spring 20, causing the elevation 30 of rod 17, support 16, and consequently the enlargements 15, are raised from the seats 7. The liquid then pours through the ports 6 to pipe 16 and out through the openings 11 to the bristles 4, which are thus constantly 35 kept moistened.

Should the flow of the liquid become too great, the finger pressure on the presser bar 19 would be relaxed and consequently rod 17 would be pulled downwardly by the 40 spring 20 and the support 16, and valve stems 13 would be lowered and the flow through the ports cut off.

Having thus fully described my invention, what I claim as new and desire to set 45 cure by Letters Patent is:—

1. A fountain brush comprising a hollow body casing adapted to hold a supply of fluid, the bottom portion of said body casing provided with openings extending there- 50 through, a rod slidably mounted in said casing, a presser bar connected to the upper end of said rod, a support connected to the inner end of said rod and formed with enlarged perforated ends, stems disposed within said 55 body and adapted for adjustment to regu-

late said openings, the enlarged ends of said support adapted for movement on said stems to open and close said openings.

2. A fountain brush comprising a hollow body casing adapted to hold a supply of 60 fluid, the bottom portion of said body casing provided with openings extending there- through, a rod slidably mounted in said casing, a support connected to the inner end of said rod and formed with enlarged perfor- 65 ated ends, stems disposed within said body and adapted for adjustment to regulate said openings, the enlarged ends of said support adapted for movement on said stems, means for actuating said support to open and close 70 said openings, and regulating means for the said stems.

3. A fountain brush comprising a fluid reservoir, the bottom of said reservoir pro- 75 vided with outlet openings, a rod slidably mounted in the top of said reservoir, a presser bar connected to the protruding end of said rod, a supporting element disposed within said reservoir and formed with en- 80 larged perforated ends, said ends provided with openings, stems arranged within said reservoir and passing through the openings in said enlarged ends of the supporting element, said stems adapted for adjustment for regulating the outlet openings, the en- 85 larged ends of said supporting element forming valves, for opening and closing said outlet openings, and means for regulat- ing the outlet openings.

4. A fountain brush comprising a fluid 90 reservoir, the bottom of said reservoir pro- vided with outlet openings, a rod slidably mounted in the top of said reservoir, a sup- 95 porting element arranged on said rod and disposed within said reservoir, said sup- porting element formed with enlarged per- forated end portions, stems arranged within said reservoir and passing through the per- forations in said enlarged end portions of the supporting element, said stems adapted 100 for adjustment, for regulating the outlet openings, the enlarged end portions of said supporting element forming valves, for opening and closing said outlet openings, means for actuating said valves, and means 105 for adjusting said stems with respect to the said openings.

In witness whereof I have hereunto set my hand.

EMILE LAROCHE.
